UNITED STATES PATENT OFFICE.

CLYDE MCKELLAR, OF CHICAGO, ILLINOIS.

AMALGAMATOR.

1,003,118.

Specification of Letters Patent. Patented Sept. 12, 1911.

Application filed August 1, 1910. Serial No. 574,987.

To all whom it may concern:

Be it known that I, CLYDE MCKELLAR, a citizen of the United States, residing at Chicago, in the county of Cook and State of Illinois, have invented certain new and useful Improvements in Amalgamators, of which the following is a specification.

My invention relates to mining appliances and has particular reference to improvements in amalgamating machines.

The object of the invention is to provide an amalgamator of increased efficiency, economy and speed of operation, to which end I provide among other things, for a series of riffles arranged to form a continuous path and to keep the mercury in circulation throughout these riffles or along this path.

My invention consists in the novel construction, combination, operation and arrangement of parts, hereinafter described in detail, illustrated in the appended drawing and incorporated in the subjoined claims.

In the drawing—Figure 1 is a plan view, partly broken away, of an apparatus embodying my invention, minus the supporting frame therefor shown in Fig. 2. Fig. 2 is a vertical section of the complete machine, taken substantially on line X—X of Fig. 1.

In the above named views are shown an amalgamator with a novel arrangement of supply tank, or hopper, and a "riffle box" with the well known step-by-step arrangement of riffles, but with the initial riffles at the bottom instead of at the top of the riffle box, as in the usual arrangement. These riffles also form a continuous or spiral path both ends of which communicate with the mercury well or trough, and the mercury is caused to circulate from the well to and along the riffles and back again thus insuring an even distribution of mercury coating for the riffles, activity in both the mercury and the precious metal to the end of facilitating amalgamation and to prevent the escape of particles of precious metals lodged in any part of the riffles.

The process of amalgamation carried out by my apparatus is further designed to take precious metal out of water where its presence is indicated merely by the coloring of the water.

Referring, now, in detail, to the several views, 2 represents a supporting frame which may be of any suitable design or construction. Within the frame 2 is sup-

ported in any approved manner a substantially conical hopper 3, having an opening 4 in its apex or bottom. The upper edges of the hopper are curved downwardly and then upwardly to form an annular trough or receptacle 5, which along its periphery is provided with one or more outlets 6. Underneath the hopper 3 is revolvably mounted a riffle box, riffle container or riffle carrier 7, the configuration of which is substantially that of an inverted truncated cone and corresponding in contour substantially to the form of the hopper 3, whereby the two parts 3 and 7 practically nest into each other and take up substantially no more ground space than one of the parts alone would. The riffle carrier 7 is secured to a vertical shaft 8. This shaft is provided with a driving pulley 9 to which power may be transmitted in any suitable manner and from any suitable source.

10 and 11 are bearings for the shaft 8 and 12 is a hub secured to the shaft and to a false bottom 13 of the riffle carrier which bottom is immediately supported on said hub. Further support for the riffle-carrier with respect to the shaft 8 is provided by a central conical bottom 14 formed, as shown in Fig. 2, by bending up the lower edges of 85 a sheet iron carrier and securing them to the shaft, thus affording not only a brace or braces between the carrier and the shaft, but also providing an inclined bottom directing the material by the force of gravity to 90 riffle-sides of the carrier to be hereinafter described.

Within the vertical plane of the frame 2 and the horizontal plane of the bottom, or near thereto, is an annular mercury trough 95 or well 15. Within the riffle-carrier and on its inclined sides are a series of superposed riffles which are connected to form a spiral. These riffles may be made of pipe split lengthwise to form troughs. These troughs, 100 or the spiral trough, are secured by fastening one edge of the trough to the side of the carrier in inverted position, that is, with the opening of the trough down, as shown in Fig. 2, the flow of material, as hereinafter 105 described, being upward instead of downward. The riffles in their superposed, or step-by-step arrangement are indicated by the figure 16, the upper or intake end of the spiral forming the riffles is indicated at 110 17, which may also be termed the topmost riffle. This topmost riffle, or its intake end,

communicates with a pipe 18 which extends from the topmost riffle down into the mercury well, or annular trough, and the lower end of this pipe, has a horizontally bent portion 19 which is arranged to dip into the mass of mercury. The bend 19 has its opening facing the direction of motion as shown in Fig. 2, so that rotation of the riffle-carrier in the direction of the arrow in Fig. 1 will force mercury into the mouth of the pipe 19. The lower end of the spiral is indicated at 20 and may also be termed the lowermost riffle and the outlet end of the spiral path when the point 17 is considered as the inlet end. The outlet end 20 is also provided with a pipe, which is labeled 21 and is provided with a bend 22 which dips into the fluid mercury mass, but in this instance the bend is away from the direction of motion when the riffle-carrier is rotated to the left, or in the direction of the arrow in Fig. 1. When thus rotated gravity will to some extent assist the flow along the spiral on account of its slight inclination in the direction of flow. However, by reversing the direction of motion the bend 22 will become the intake and the bend 19 the outlet under centrifugal force imparted by the rotation of the riffle-carrier, to be more particularly referred to. The riffle carrier is equipped with one or more brooms or brushes 23 which may be conveniently secured to a horizontal flange 24 formed on the upper edge of the riffle-carrier.

25 indicates a quantity of mercury in the circular trough 15 and 26 water.

27 is a fender or splash-guard mounted on the pipe 19 as shown in Fig. 2. The pipe 21 may be likewise equipped. This 40 guard 27 receives the spray due to the agitation of the water by the pipe 18. The purpose of the water is to serve as a wash to remove impurities and the trough may be supplied by a continual flow of water 45 from any suitable running water supply.

In operation, when the concentrates, water, or other precious mineral-bearing material is poured into the hopper 3 and the shaft 8 is rotated in the direction, say, of the arrow in Fig. 1, such concentrates or the like, will be carried by the rotation of the carrier upwardly along its inclined sides and over the riffles until discharged over the upper edge or flange 24 into the annular trough 5 whence it will be swept to one or more suitable opening or openings 6. Under the centrifugal action the concentrates and other matter in the riffle-box or riffle-carrier will have a tendency to fly outwardly on horizontal lines and the movement of the bend 19 with its opening or mouth facing the direction of motion will force mercury from the well up into the uppermost riffle 17 and thence to the outlet 22. If the motion is in a di-

rection opposite to that indicated by the arrow, the mercury will be taken in at 22 and the riffle 20 will be the initial riffle with the riffle 17 and its pipe 18 the outlet. This tendency of the material to fly out in a horizontal direction will press the concentrates against the sides of the riffle-carrier and the heavier precious metal particles will be forced into the mercury thus assisting amalgamation. At the same time 75 the mercury is moving in a direction at right angles to the movement of the concentrates upwardly, or approximately so, thus assisting the amalgamation or junction of the materials. These reciprocal forces I 80 have found by actual test to be such as to take gold out of water where its presence was apparent only as a solution coloring the water brown. The circulation of the mercury also insures its distribution into every 85 part of the riffles and to traverse every part which insures the catching or taking up of any particles of gold or silver in the riffles which might otherwise escape by being lodged in some uncoated part of the riffles. 90 Another advantage gained by this circulation of the mercury is that I can cover a larger area of riffles or riffle surface with a given quantity of mercury and there being no waste of material by having a body of 95 unused mercury lying still where no particles of precious metal happen to pass, all of the mercury will be compelled to act until fully laden with mineral.

In my riffle-box or riffle-carrier I also 100 provide at least one riffle and mercury-pocket 28 which is an annular trough substantially like the troughs 16, but unconnected with the mercury-well and designed to hold the mercury without the motion 105 imparted by the intake and outlet pipes and the spiral above-described. The concentrates will therefore pass over the riffles or riffle 28 and against the body of mercury therein before encountering the traveling 110 mercury. Under certain conditions I employ only riffles 28 and dispense with the circulating system which I have found indispensable under other conditions. I prefer, ordinarily, to combine both to the extent of at least one annular riffle 28, as 115 shown in the accompanying drawing, though each alone represents a separate construction and both together represent a third construction.

Having thus described my invention, I claim as new and desire to secure by Letters Patent—

1. The combination with a dish-shaped hopper, of a similarly formed riffle-carrier into which said hopper is substantially nested, a mercury well or trough, riffles arranged in the form of a spiral, an inlet pipe from said well or trough to one end of said spiral, an outlet from the opposite 125 130

end of said spiral leading into said trough or well, said pipes having horizontally bent ends in said trough or well as set forth, and means for rotating said carrier, spiral and 5 pipes.

2. The combination with a hopper having an opening in the bottom thereof and sides converging toward said opening, of a riffle-carrier having upwardly and outwardly inclined sides, an annular riffle in the form of an inverted trough, a spiral riffle, a mercury-trough or well, an inlet pipe from said well to said spiral and arranged to scoop up mercury from said well into said spiral, 10 an outlet pipe from said spiral to said well, 15

an annular trough arranged to receive concentrates flowing from said carrier, an outlet pipe from said annular trough, a brush on said carrier arranged to sweep contents from said annular trough, and means for 20 rotating said carrier as and for the purpose set forth.

In testimony whereof I have hereunto set my hand in the presence of two subscribing witnesses.

CLYDE McKELLAR.
